UNITED STATES PATENT OFFICE.

HANS PETERSEN, OF DAVENPORT, IOWA, ASSIGNOR TO THE LINOGRAPH COMPANY,
OF DAVENPORT, IOWA, A CORPORATION.

MAGAZINE FOR TYPESETTING-MACHINES.

1,356,786.

Specification of Letters Patent. Patented Oct. 26, 1920.

Application filed November 20, 1919. Serial No. 339,255.

To all whom it may concern:

Be it known that I, HANS PETERSEN, a citizen of the United States, and a resident of Davenport, in the county of Scott and State of Iowa, have invented certain new and useful Improvements in Magazines for Typesetting-Machines, of which the following is a specification, reference being had therein to the accompanying drawing.

10 This invention relates to improvements in typographical machines of that class employing a plurality of magazines with supporting and shifting means therefor whereby any of the magazines may be brought 15 into operative relation with the assembling and distributing mechanisms.

The object of the present invention is to improve machines of the character referred to, to provide an improved multiple magazine system of a comparatively simple nature, providing for the employing and efficient manipulation of fractional length magazines, and also for the use of such lighter fractional length magazines and full 25 length magazines together.

The invention, with other objects and advantages thereof, and the particular construction, combinations and arrangement of parts comprising the same, will be understood from the hereinafter contained detailed description, when considered in connection with the accompanying drawing forming part hereof and illustrating one embodiment of the invention.

35 In the drawing:—

Figure 1 is a side elevation of a linotype machine equipped with a multiple magazine and supporting and shifting means therefor in accordance with the present invention.

40 Fig. 2 is a front elevation.

The invention comprehends the use of a fractional length magazine supported on the frame of the machine in operative position, one or more fractional length magazines, and a support for the same vertically adjustable to position them in operative position with the first mentioned fractional length magazine, the latter being adapted to serve as an entrance section for the other fractional length magazine or magazines. The invention further contemplates the use of one or more full length magazines with the fractional length magazines before referred to, said full length magazine or magazines being carried and moved into

operative position by the vertically adjustable magazine supporting frame, and the fractional length entrance section magazine being supported upon the main frame to be lifted therefrom out of operative position 60 through the medium of the vertically adjustable magazine supporting frame.

While in the drawing, I have illustrated, by way of example, a specific embodiment of the invention, it will, of course, be understood that modifications and changes in the particular construction shown, variations in the number of fractional length and full length magazines employed and the carrying out of the invention in other forms as 65 will appeal to those skilled in the art and falling within the scope of the appended 70 claims, may be practised without departing from the spirit of the invention.

In the drawing, 1 designates the frame 75 of the machine, 2 the distributor, and 3 a portion of the assembler entrance. These parts may be of any suitable form, the construction shown being one of the well known types and only indicated in a general 80 way.

5 designates the fractional length magazine supported on the frame 1 of the machine at the upper portion thereof and toward the rear in operative relation with the distributor 2. This fractional length magazine is not intended for the storage of matrices but is adapted to serve as an entrance section for one or more fractional length magazines, which are adapted to be 85 moved vertically into operative position with said entrance section magazine 5 and the assembler entrance 3. In the present instance, two of such fractional length magazines 6 and 7 are shown carried by a 90 vertically adjustable frame 9, said frame being mounted on a shaft or plunger 10 slideable in a casing 11, any suitable adjusting means being associated with the plunger, for instance, a screw and nut gear as illustrated in the drawing, the nut 12 being actuated by a pinion 13 driven in any desired 95 way.

On the magazine supporting frame 9 are mounted one or more full length magazines, 105 there being only a single one 14 in the present showing, said full length magazine or magazines being adapted to be moved vertically into operative relation with the distributor 2 and assembler entrance 3, the en- 110

trance section magazine 5 being supported upon the frame 1 of the machine to allow for the same to be lifted out of operative position and the full length magazine 14 moved into operative position. Any suitable supporting means for the entrance section magazine that will answer the purpose may be employed. In the construction shown, the frame 1 is provided with supporting ledges or bars 16 at each side and the entrance section magazine 5 has laterally projecting lugs 17 at each end to rest upon the ledges or bars 16. At their forward ends the bars 16 are provided with hook portions or angular projections 18 adapted to engage the forward laterally projecting lugs 17 and hold the same on the bars. The fractional length magazines 6, 7 and the full length magazine 14 are provided with projections or lugs 19 at the upper sides thereof and at their under sides with ribs or lugs 20, the magazines carried by the magazine supporting frame excepting the lowermost magazine resting upon the projection or lugs of the one next below in the stack, and the ribs or projections 20 at the under sides of the magazines engaging the sides of the projections or lugs 19 and serving to maintain the stack of magazines in proper position. The fractional length magazine 5 also has ribs or projections 20 at the under side thereof adapted to coöperate, in a similar manner as herein-after explained, with the pairs of projections or lugs 19 at the upper side of the rear part of the full length magazine 14.

In the drawing, the magazines are all shown in their lowermost positions, the upper fractional length magazine 5 being supported upon the ledges or bars 16, and the fractional length magazine 6 in operative position therewith, the matrices passing from the distributor mechanism at the top of the main point through fractional magazine 5, into the fractional magazine 6, from which they may be discharged into the assembler entrance 3. By raising the magazine supporting frame, the fractional magazine 7 may be positioned in operative relation with the fractional length magazine 5 and the assembler entrance 3, said fractional length magazine 5 then serving as an entrance section for the fractional magazine 7, and so on throughout the series of fractional length magazines carried by the magazine supporting frame. As the last of the series of fractional length magazines or lowermost fractional length magazine is brought to operative position, the lugs or projections 19 at the upper side of the rear part of the full length magazine 14 will be positioned directly in front of the lugs 20 on the fractional length magazine 5 and so that the fractional length magazine 5 will

also rest thereupon. A further advance of the magazine frame to bring the lowermost magazine 14 into operative position will result in the fractional length magazine 5 being lifted from its support on the main frame beyond operative position, and the full length magazine 14 being moved into operative relation with the distributor 2 and assembler entrance 3. When the adjustment is reversed and the magazine supporting frame lowered, as soon as the fractional length magazine 5 reaches the supporting bars 16, the lateral projections 17 will engage with the bars, and said magazine 5 will then be in its normal position to coöperate with any one of the fractional length magazines carried by the magazine supporting frame.

What I claim is:

1. In a typographical machine, the combination of a full length magazine and a plurality of fractional length magazines arranged in vertical series one above another, a fractional length magazine adapted to be positioned in operative position separately with other of the fractional length magazines, and shifter means for the magazines.

2. In a typographical machine, the combination of a full length magazine, and a plurality of fractional length magazines arranged in vertical series one above another, a fractional length magazine being supported at the upper part of the frame in operative position and adapted to serve separately as an entrance section for each of the other fractional length magazines, and shifting means for the magazines.

3. In a typographical machine, the combination of a plurality of fractional length magazines movable vertically into operative position, one of said magazines being adapted to serve separately as an entrance section for each of the other magazines, means for supporting said fractional length magazine on the frame at the upper part thereof, a lower full length magazine movable vertically into operative position, means for vertically shifting the other fractional length magazines into operative position to coöperate with the entrance section magazine, and for moving said fractional length magazine out of operative position and positioning the full length magazine in operative position.

4. In a typographical machine, a main frame, supporting means on the main frame, a fractional length magazine adapted to rest upon said supporting means in operative position, a vertically adjustable magazine supporting frame, a lower full length magazine carried by the magazine supporting frame, a fractional length magazine supported on the magazine supporting frame above the full length magazine, and adjusting means for the magazine supporting frame, said

magazine supporting frame being adapted to move the fractional length magazine carried thereby into operative position with the other fractional length magazine supported 5 on the main frame, and to lift both of the fractional length magazines out of operative position, and position the full length magazine in operative position.

5. In a typographical machine, the combination of a main frame, bars at opposite sides of the main frame, a fractional length magazine provided with lateral projection lugs to rest upon said bars and support said magazine in operative position, a vertically 10 adjustable magazine supporting frame, a lower full length magazine carried by the magazine supporting frame, a fractional length magazine supported on the magazine supporting frame above the full length magazine, and adjusting means for the magazine 15 supporting frame, said magazine supporting frame being adapted to move the fractional length magazine carried thereby into operative position with the other fractional 20 length magazine supported on the main frame and to lift both of the fractional length magazines out of operative position, and to position the full length magazine in 25 operative position.

30 6. In a typographical machine, the com-

bination of a main frame, supporting bars at opposite sides of the main frame, a fractional length magazine provided with lateral projecting lugs to rest upon said bars and support the magazines in operative position, each of said bars having at one end thereof a projecting part to engage one of the lateral projecting lugs of the magazine and hold the same in position on the bars, a vertically adjustable magazine supporting 35 frame, a lower full length magazine carried by the magazine supporting frame, a fractional length magazine on the magazine supporting frame above the full length magazine, and adjusting means for the magazine 40 supporting frame, said magazine supporting frame being adapted to move the fractional length magazine carried thereby into operative position with the other fractional length magazine supported on the main 45 frame and to lift both of the fractional length magazines out of operative position, and to position the full length magazine in 50 operative position.

In testimony whereof I hereunto affix my 55 signature in the presence of two witnesses.
